US0D1060043S

(12) **United States Design Patent** (10) Patent No.: **US D1,060,043 S**
(45) Date of Patent: ** Feb. 4, 2025

(54) **CONTAINER**

(71) Applicant: **Conopco, Inc.**, Englewood Cliffs, NJ (US)

(72) Inventors: **Oliver James Boulton**, Chester (GB); **Hannah Brzezinka**, Merseyside (GB)

(73) Assignee: **CONOPCO, INC.**, Englewood Cliffs, NJ (US)

(**) Term: **15 Years**

(21) Appl. No.: **29/925,922**

(22) Filed: **Jan. 26, 2024**

Related U.S. Application Data

(62) Division of application No. 29/758,324, filed on Nov. 13, 2020, now Pat. No. Des. 1,034,185.

(57) **CLAIM**

The ornamental design for a container as shown and described.

DESCRIPTION

FIG. 1 is a perspective view of a container, showing our new design;

FIG. 2 is a front view of the container of FIG. 1;

FIG. 3 is a rear view of the container of FIG. 1;

FIG. 4 is a left side view of the container of FIG. 1;

FIG. 5 is a right side view of the container of FIG. 1;

FIG. 6 is a top view of the container of FIG. 1; and,

FIG. 7 is a bottom view of the container of FIG. 1.

The broken lines in the drawings depict portions of the container that form no part of the claimed design.

1 Claim, 6 Drawing Sheets
